ELECTRIC CIRCUIT BREAKER

Edward J. Frank, Springfield, and Virgel E. Phillips, Philadelphia, Pa., assignors to General Electric Company, a corporation of New York

Application October 7, 1950, Serial No. 189,026

8 Claims. (Cl. 200—147)

1

This invention relates to electric circuit breakers and more particularly to circuit breakers having main current-carrying contacts and arcing contacts arranged in parallel therewith across which the arc to be interrupted is drawn during a circuit opening operation, such, for example, as the circuit breaker disclosed in U. S. Patent 2,280,616, Baskerville, which is assigned to the same assignee of this application.

In circuit breakers of this type and under certain interrupting conditions the arc may blow back from the arcing contacts to establish itself at the current-carrying contacts and as a result of such transfer, the breaker may fail to interrupt while the current-carrying contacts may suffer damage from such arcing which they are not well adapted to withstand. Circuit breakers of this type usually are provided with arc blow-out and quenching means such as an arc chute which is adapted to extinguish an arc initiated across the arcing contacts only if the arc travels into the chute in a direction away from the main contacts. Thus, if the arc is allowed to strike back across the first-opened current-carrying contacts, its extinguishment may become difficult or impossible for it has moved out from the effective quenching zone. Transfer of the arc back from the arcing to the current-carrying contacts may be caused by unstable magnetic conditions aggravated by an uncontrolled ionized gas condition emanating from the arcing zone into the region of the current-carrying contacts.

Accordingly, an object of the invention is to provide a novel arrangement of blowout means and an associated arc runner for a circuit breaker having main current-carrying contacts and arcing contacts, which arrangement is effective to segregate the fixed arcing contacts from the fixed current-carrying contacts and which effectively insures that the initially drawn arc will not immediately wander and attach itself to the current-carrying contacts.

Another object of the invention is to provide means for controlling the disposition of hot ionized gases formed at the arcing contacts so as to prevent the blow-back of such gases into the region of the current-carrying contacts thereby further to minimize the hazard of an arc striking back at the current-carrying contacts.

According to the invention a barrier in the form of an arc runner is disposed in the region intermediate the arcing and main contacts, which barrier is provided with an opening therein through which the movable arcing contact is movable. Thus the arc is drawn in a region

which is shielded from the main contact and so is prevented from transferring thereto during the initial opening movement before the movable arcing contact tip emerges from the opening in the arc runner. As the movable arcing contact is passing through the opening in the arc runner, magnetic blowout means become effective to urge the arc in a direction into the arc chute and away from the main current-carrying contacts. Furthermore, we provide gas-deflecting means for effectively diverting the hot ionized gases generated by the arc into the chute, to thereby augment the blow-out effect as well as diverting these gases away from the current-carrying contacts.

The invention will be better understood with reference to the accompanying drawing in which Fig. 1 is a side view partially in section of a circuit breaker embodying the invention; and in which Fig. 2 is a view along the line 2—2 of Fig. 1.

With reference to Fig. 1 the circuit breaker shown therein includes a terminal 1 comprising a conductor stud and a corresponding stud terminal 2 which are fixed in position with respect to the circuit breaker frame (not shown). The fixed contact structure generally designated at 3 is electrically connected with the terminal 1 while the movable contact arm 4 is pivoted and electrically contacted at 5 to terminal stud 2. Contact arm 4 is rotatable about pivot 5 by the insulated operating rod 6 which is pivoted to the operating arm 4 at 7. Motivating force for the contacts is supplied through the actuating member 8 and the coupling means of operating rod 6 is adjustable according to Patent No. 2,590,765, Frank et al., granted March 25, 1952, assigned to the assignee of this application. Fixedly mounted on and movable with the contact operating arm 4 is a broad movable current-carrying contact 9 and a narrow movable arcing contact 10.

Electrically connected with conductor stud 1 is a conducting member 11 to which is fastened the curved contact retaining member 11a thereby to form a pocket for receiving therein the anchored ends of the main contact fingers. Main current-carrying fixed contact fingers 12 are biased for rotation in the clockwise direction about the pivot comprising the curved portion 13 of member 11 by means of compressional spring 14 whose associated guide pins 15 operate in the retainer member 11a. Fixed arcing contact 16 is mechanically and electrically connected to the member 11 by means of the shouldered conducting pin 17 riveted over at 18. As is best seen in Fig. 2 fixed arcing contact 16 comprises a pair of finger type

contacts which are biased toward each other about pin 17 by compressional springs 13 and 23 to embrace between the tips thereof the cooperating tip of the movable arcing contact 10. As is clearly shown in both Figs. 1 and 2 movable arcing contact 10 is provided with a considerable wiping movement in order to insure that these arcing contacts will not be separated to draw the interrupting arc until after a safe separation of movable main contact 9 from the fixed main contact fingers 12 has been established. In this way the contacting surfaces of contacts 9 and 12 do not become pitted and merely serve as current carrying contacts when the breaker is closed.

As already explained, the arc drawn between the arcing contacts may, under certain conditions, tend to back across to the current-carrying contacts and thereby hazard a failure to interrupt and cause damage to such contacts which are unprotected by arc-resistant tips such as are provided for the arcing contacts. Furthermore the blowout effect diminishes toward the main current-carrying contacts so as to become less effective in driving the wandering arc into the chute which is a necessary prerequisite to extinguishment. Thus it is imperative that an arc must not strike or reform across the main current-carrying contacts 9 and 12.

In order to prevent such striking of the arc between the main current-carrying contacts, an arc runner 21 in the form of a barrier or gas directing means is provided according to the invention, and is inserted in the region between the fixed arcing contacts 16 and the fixed current-carrying contact fingers 12. Insulation, such as 21a and 21b, is provided for electrically isolating the runner 21 from the associated conducting parts so that runner 21 constitutes an effective shunt path independent of the contact structure. Thus, when the arc is drawn initially and before the arcing tip of movable arcing contact 10 moves through the slot-like opening 22 provided in the arc runner 21, the arc cannot move from the arcing contacts to the current-carrying contacts due to the barrier effect of the arc runner 21. Furthermore, in order to prevent ionized gases formed at the arcing contacts, which issue as a downward jet through the slot 22, from spreading toward the current-carrying contacts 9 and 12 which might initiate a breakdown, a deflecting barrier 23 is provided as a further feature according to the invention. Barrier 23 constitutes a broad flange and is integral and movable with the arcing contact 10 and, as is clearly evident from Fig. 1, the flow of gases downwardly through the opening 22 will impinge on the deflecting surface of baffle 23 so that the gases are directed toward the left into the arc chute structure generally designated by the numeral 24. Of course the baffle 23 need not be affixed to the contact 10 and could be fixed in position with respect to the opening 22. If desired the barrier could be provided with an opening through which the contact 10 would be movable.

As the arcing contact 10 moves downwardly during an opening stroke, and as the arcing tip thereof is passing through the slot 22 in the arc runner 21 the upper arc root transfers from the fixed arcing contact 16 to the arc runner 21 thereby introducing in series with the arc the first blowout coil 25 which is connected between conductor stud 1 and arc runner 21. At this point, it will be understood that current flowing through the hinged contact arm 4 and the arc then proceeds via the insulated arc runner 21 and

the coil 25, the current path through the runner and coil constituting an alternative path for the initial interrupting arc circuit comprising the arcing fingers 16, pin 17 and conducting member 11. Thus, the runner 21 really constitutes a part turn coil in series with the blowout coil 25. As is well known, the effect of this blowout coil is to establish a magnetic condition which urges the arc in a direction toward the left end and into the arc chute 24. As the contact 10 continues to move downwardly, the lower root of the arc will transfer from the arcing contact 10 to the arc runner 26 thereby introducing in series with the arc and blowout coil 25 the lower blowout coil 27 to thus augment the blowout effect upon the arc toward the left. Because the coil 27 is connected with conductor stud 2 through the conducting strap 28, the interrupting circuit is now shunted completely around the contact arm 4. If not yet extinguished, the arc will continue to move to the left so that its upper root will transfer from the arc runner 21 to the upper arc runner 29. Thus, the third blowout coil 30 is inserted in series with blowout coils 25 and 27 by reason of its being connected across the insulating block 31 which separates the lower runner 21 from the upper runner 29. In the particular embodiment shown, the blowout effect of these three coils upon the arc whereby it is driven to extinction in the chute 24 will be adequate to insure the interruption of all currents within the rating of the circuit breaker.

Thus by installing the fixed arcing contact within a pocket comprised by the shielding arc runner 21 having but one vent therefrom, viz. the opening 22, all ionized gas products of the initially drawn arc are directed therethrough in a concentrated stream downwardly; after which the deflecting barrier associated with the movable arcing contact is effective in diverting this ionized stream safely into the arc chute directly away from the main current-carrying contacts.

While we have shown and described a particular embodiment of the invention we do not wish to be limited thereto and intend in the appended claims to cover all changes and modifications as fall within the true spirit and scope of the invention.

What we claim as new and desire to secure by Letters Patent of the United States is:

1. An electric circuit breaker comprising a pair of relatively movable current-carrying contacts, a pair of relatively movable arcing contacts, arc runner means disposed in the region intermediate said pairs of contacts, an opening in said arc runner through which a movable one of said arcing contacts is movable, and means for urging the arc drawn between said arcing contacts in a direction away from said current-carrying contacts.

2. An electric circuit breaker comprising fixed and movable current carrying contacts, fixed and movable arcing contacts arranged in parallel with said current-carrying contacts, stationary gas directing means partially surrounding said fixed arcing contact and having a portion thereof disposed intermediate said fixed current-carrying and said fixed arcing contacts and insulated therefrom for causing the arc gases produced at said arcing contacts to move in one general direction, and baffle means disposed in the path of movement of said arc gases when said gases are moved in said one general direction, said baffle means being effective to deflect said

gases in another general direction away from said current-carrying contacts.

3. An electric circuit breaker comprising fixed and movable current-carrying contacts, fixed and movable arcing contacts arranged in parallel with said current-carrying contacts, gas directing means partially surrounding said fixed arcing contact and having a portion thereof disposed intermediate said fixed current-carrying and said fixed arcing contacts and insulated therefrom for causing the arc gases produced at said arcing contacts to move in one general direction, and baffle means movable with said movable arcing and current-carrying contacts and disposed in the path of movement of the arc gases when moved in said one general direction for deflecting said gases in another general direction away from said current-carrying contacts.

4. An electric circuit breaker comprising a pair of relatively movable current-carrying contacts, a pair of relatively movable arcing contacts, arc runner means disposed in the region intermediate said pairs of contacts, an opening in said arc runner through which a movable one of said arcing contacts is movable, means for urging the arc drawn between said arcing contacts in a direction away from said current-carrying contacts, and gas-deflecting means disposed with respect to said arcing contacts so as to deflect the hot ionized gases caused by the arc between said arcing contacts in a direction away from said current-carrying contacts.

5. An electric circuit breaker comprising a pair of relatively movable current-carrying contacts, a pair of relatively movable arcing contacts, barrier means including a portion of an arc runner disposed between one of said arcing contacts and one of said current-carrying contacts and partially surrounding said one arcing contact for directing the ionized gases formed upon separation of said arcing contacts in a predetermined direction, and gas-deflecting means disposed in the path of movement of said gases and arranged with respect to said barrier means so as to deflect effectively said gases in a direction away from said current-carrying contacts.

6. An electric circuit breaker comprising a pair of relatively movable current-carrying contacts, a pair of relatively movable arcing contacts, arc runner means disposed in the region intermediate said pairs of contacts, an opening in said arc runner through which a movable one of said arcing contacts is movable, means for urging the arc drawn between said arcing contacts in a direction away from said current-carrying contacts, and a gas-deflecting surface dis-

posed on said movable arcing contact for deflecting the hot ionized gases caused by the arc drawn between said arcing contacts issuing through said opening to be thereafter diverted in a direction away from said current-carrying contacts.

5 7. An electric circuit breaker comprising electrically interconnected fixed arcing and current-carrying contacts, movable arcing and current-carrying contacts movable into and out of engagement respectively with said fixed arcing and main contacts, an arc runner interposed between said fixed arcing and current-carrying contacts and insulated therefrom, said arc runner being provided with an opening through which said movable arcing contact is movable, and magnetic blowout means interconnected between said fixed arcing and current-carrying contacts and said arc runner for exerting a force on the arc drawn between said arcing contacts in a direction away from said current carrying contacts.

10 8. An electric circuit breaker comprising electrically interconnected fixed arcing and current-carrying contacts connected to one terminal of the breaker, movable arcing and current-carrying contacts connected to another terminal of the breaker and movable into and out of engagement respectively with said fixed arcing and current-carrying contacts, said contacts and terminals being arranged in a loop circuit, an arc runner interposed between said fixed arcing and current-carrying contacts and insulated therefrom, said arc runner being provided with an opening through which said movable arcing contact is movable and being disposed with respect to said loop circuit so that the magnetic effect thereof aids the arc in transferring from said fixed arcing contact to said arc runner, and magnetic blowout means interconnected between said fixed arcing and current-carrying contacts and said arc runner for exerting a force on the arc drawn between said arcing contacts causing the arc to move in a direction away from said current-carrying contacts after transfer of the arc to said arc runner.
